UNITED STATES PATENT OFFICE.

KATHERINE K. GRANT, OF NEW YORK, N. Y.

DESIGN FOR A DOLL OR EFFIGY.

45,873.

Specification for Design.

Patented June 2, 1914.

Application filed March 12, 1914. Serial No. 824,319. Term of patent 3½ years.

To all whom it may concern:

Be it known that I, KATHERINE K. GRANT, a citizen of the United States, residing at No. 628 West One Hundred and Fourteenth street, New York city, in the county of New York and State of New York, have invented a certain new, original, and ornamental Design for Dolls or Effigies, of which the following is a specification, reference being had to the accompanying drawing, forming part thereof.

The figure is a perspective of the doll or effigy, showing my new design.

I claim:

The ornamental design for a doll or effigy, as shown.

In testimony whereof I affix my signature in the presence of two witnesses.

KATHERINE K. GRANT.

Witnesses:

MARY COTTER,
P. J. GRANT.
